UNITED STATES PATENT OFFICE.

JOHN C. ENGLISH, OF CAMDEN, NEW JERSEY.

GAS-ENGINE.

1,159,481.

Specification of Letters Patent.

Patented Nov. 9, 1915.

Application filed June 8, 1911. Serial No. 631,912.

To all whom it may concern:

Be it known that I, JOHN C. ENGLISH, a citizen of the United States, and a resident of Camden, county of Camden, and State of New Jersey, have invented certain new and useful Improvements in Gas-Engines, of which the following is a specification.

The main objects of this invention are to provide, in a gas engine, an improved valve and improved valve actuating mechanism; and to provide other improvements as will appear hereinafter.

In the accompanying drawings Figure 1 is a fragmentary longitudinal central section, of a gas engine constructed in accordance with this invention; Fig. 2 a top plan view of the same; Fig. 3 a side elevation of the same; Fig. 4 a reduced end elevation of a detail of the same; and Fig. 5 a reduced side elevation of a modified form of a portion of the same.

Referring to the drawings, one embodiment of this invention comprises a cylinder 1, in which, according to the usual practice, reciprocates any suitable piston 2 which is pivotally connected to the inner end of a connecting rod 3, the outer end of which is connected to rotate a crank shaft or main driving shaft 4.

30 The cylinder is provided centrally in the head thereof with the spark plug 5, having terminals 6 and 7 within the end of the cylinder for generating a spark to explode a mixture of gas and air within the cylinder. 35 The cylinder is also provided with a water jacket 8, forming a compartment 9 for the passage of water for cooling the cylinder.

For supplying the cylinder with a combustible mixture of gases, there is arranged upon one side thereof adjacent to the inner end a substantially cylindrical valve case 15, one side of which is provided with a continuous, flat, annular flange 16, which is rigidly secured by means of cap screws 17 to a corresponding flat annular seat 18 provided therefor on the adjacent side of the cylinder 1. The valve case is provided with a water jacket 20, providing a compartment 21 for the passage of water and communicating with the water compartment 9 of the cylinder 1 through an opening 22.

The central portion of the inner surface of the valve case 15 is in the form of a concave,

conical valve seat 25, coaxial with which and extending through the casing 15 is a cylindrical aperture 26, the walls of which form a bearing for a cylindrical valve stem 27, which extends through the aperture 26 and projects outwardly from the casing. The valve seat may be slightly truncated as shown in the drawings to provide a narrow annular shoulder 28 surrounding the valve stem, although this is not imperative.

The conical valve seat 25 is provided with a plurality of elongated ports 30, arranged radially with respect to the seat. The end walls 31 and 32 of each of these ports are concentric with the vertex of the seat 25 and the longitudinal side walls 33 are preferably straight, converging inwardly toward the vertex of the seat. These ports 30 open through the seat into an annular passage 35 provided therefor in the casing 15, coaxial with the seat, and the ports communicate through this annular passage with a tubular inlet 36, which projects outwardly from the valve casing 15 and to which is connected a supply pipe for conducting a combustible mixture of gases into the inlet 36.

For quickly opening or closing the ports 30 in the conical valve seat 25 there is provided a conical valve 40, which is rigidly secured to the inner end of the valve stem 27 by means of a pin 41 extending through an inwardly projecting hub 42 provided on the valve, and through the valve stem 27, or in any other suitable manner. This conical valve fits snugly against the conical seat 25 throughout its full extent, the valve being truncated where the seat is truncated. The outer margin of the valve 40 projects inwardly from the valve casing 15 into a cylindrical recess 43 provided therefor in the outer surface of the cylinder 1. The inner surface of the valve 40 is preferably concave and conical from the hub out to its periphery to provide a compartment 45 between the valve and the cylinder to receive the gaseous mixture passing through the valve. The compartment 45 is in permanent communication with the clearance space or compression space 46 of the cylinder through a lateral port 47 provided therefor in the wall of the cylinder. The valve 40 is provided with a plurality of ports 50 corresponding in number, size and arrangement with the ports

- 30 in the valve seat, so that all the ports in the valve will register with all of the ports in the seat when the valve is in position for that purpose.
- 5 For yieldingly holding the valve 40 against its seat 25, a spiral spring 55 surrounds the outer end of the valve stem 27 and fits loosely in an annular recess 56 provided therefor in the outer surface of the 10 valve casing 15. The inner end of the spring 55 engages against the valve casing 15 and the outer end of the spring engages against a nut 57 threaded upon the outer end of the valve stem 27, the nut 57 being held adjustably in place with respect to the valve stem 15 by a lock nut 58. The spring 55 is held normally slightly compressed to maintain the valve at all times snugly against its seat.
- For oscillating the valve 40, any well known or suitable mechanism may be operatively connected to the outer end of the valve stem 27, but to secure a quick opening and closing of the ports in the valve seat by the valve, the outer end of the valve stem 27 20 is preferably provided with a crank arm 60, rigidly secured thereto, the inner end of the arm preferably being provided with an angular opening 61 in the form of a regular polygon in cross section, having as many 25 sides as there are ports in the valve, and the outer end of the valve stem is correspondingly formed as at 62 to fit snugly in this opening. A pin 63 may be inserted through a hub 64 provided therefor on the inner end 30 of the crank arm 60, and through the end of the valve stem 27 to hold the crank arm in position.
- The outer end of the crank arm 60 may be connected to one end of a link 70 by means 35 of a bolt 71 parallel to the valve stem 27. One end of this bolt 71 fits loosely in an elongated slot 72 through the outer end of the arm 60 and extending longitudinally thereof, and the other end of this bolt fits 40 snugly in an aperture 73 through the end of the link 70. The bolt 71 is provided at one end with a head 74, and at its other end with a nut 75 and a lock nut 76 for holding the outer end of the crank arm 60 in sliding 45 engagement with the adjacent end of the link 70. The other end of the link 70 may be pivotally connected to a lug 80 rigid with the valve case by means of a stud 81 parallel to the valve stem 27, and one end of which is threaded into the lug 80 and the other 50 end of which projects outwardly from the link 70 and is provided with a nut 82 and a lock nut 83 for holding the link against movement longitudinally of the stud 81.
- 60 For oscillating the link 70 about the stud 81 an eccentric rod 85 is pivotally and adjustably connected at one end to the link 70 by means of a stud 86 which extends through the rod. The outer end of the stud is provided with a head 87 which engages against 55 the side of the eccentric rod and the inner portion of the stud is reduced in diameter to form an annular shoulder 88 and fits slidably in an elongated slot 89 extending longitudinally through the link 70 and is 60 threaded through a square nut 90 slidable longitudinally in an elongated recess 91 on the inner side of the link 70. A washer 92 surrounds the stud 86 between its shoulder 88 and the link 70. By this construction, 65 the stud 86 is held in fixed position with respect to the link 70, but may be adjusted longitudinally of the link. By adjusting the stud 86 longitudinally of the link 70, the amount of oscillation or opening of the 70 valve and the relative rapidity of its action may be varied. The other end of the eccentric rod 85 is rigidly connected to an eccentric strap 96, which surrounds an eccentric 75 shaft 98, preferably parallel to and driven from the main drive shaft 4 by a series of gears 99 in a well known manner.
- Instead of constructing and connecting the link 70 as heretofore described, one end 80 of the link may be pivoted as shown in Fig. 5, to the outer end of the crank arm 60 by means of a bolt 105 extending snugly through the crank arm, and snugly through the end of the crank, and the other end of the link may be pivotally connected to one 85 end of a second link 106, by means of a bolt 107, the other end of the second link being pivotally connected to a lug 108 rigid with the valve case by means of a stud 109. This 90 latter arrangement obviates the necessity of having an elongated slot in the crank arm and the consequent movement of the bolt 71 95 longitudinally of the arm in this slot as in the construction first described.
- A valve constructed in accordance with 100 this invention as heretofore described, is substantially noiseless in its operation and is always held snugly against its seat in such a manner as to reduce or obviate entirely the 105 possibility of a loss of compression in the cylinder owing to failure of the valve to contact with its seat, as sometimes happens with a valve which reciprocates toward and away from its seat, owing sometimes to very 110 small particles of foreign matter which are carried in between the valve and its seat. In this construction the oscillatory motion of the valve upon its seat tends to prevent any foreign matter from coming between 115 the seat and the valve, and furthermore tends to wear the valve to the seat so as to maintain at all times a tight joint. To avoid a remote possibility of any uneven 120 wearing of the valve seat or the valve, the 125 crank arm 60 may be removed from the valve stem at intervals and replaced on the valve stem after having rotated the valve through a part of the turn to bring the various 130 portions of the surface of the valve into

- contact with different portions of the surface of its seat. The angular construction of the outer end of the valve stem makes it possible to make this change conveniently 5 without removing the valve case from the cylinder, as the valve, when thus changed, will always be in the proper operative position so that the ports of the valve will register with the ports of the valve seat at the proper time, since the inner end of the arm 10 is provided with the opening 61 having the shape of a regular polygon in cross section, with as many sides as there are ports in the valve.
- 15 It is to be understood that the cylinder 1 is also provided with a second valve case 15, containing an exhaust valve which may be a conical valve constructed and actuated as hereinbefore described, but arranged to perform the functions of opening and closing a plurality of exhaust ports, leading from the cylinder. The exhaust eccentric would of course be arranged upon its shaft to have the exhaust valve alternate in its operation 25 with the inlet valve.
- Although this invention has been shown as applied to gas engines, and particularly of the explosive type, it is obvious that it is not limited to the particular form shown 30 and described but might be applied to other types of engines if found desirable. Furthermore, the invention is not limited to any particular construction disclosed, but might be applied in various constructions to meet 35 various needs without departing from the spirit of the invention or the scope of the appended claims.
- Having thus fully described this invention, I claim and desire to protect by Letters 40 Patent of the United States:
1. A gas engine including means providing a combustion chamber and a distributing chamber, a valve seat provided with a plurality of ports, a reciprocatory valve provided with an equal number of ports arranged to communicate simultaneously and respectively with said first mentioned ports to provide an equal number of separate and direct passages of communication between 45 said chambers and means to operatively vary the operative relation of the ports in said valve with the ports in said seat.
  2. The combination with a valve seat provided with a plurality of ports arranged about an axis, of a valve stem having its longitudinal axis coincident with said first mentioned axis, a valve carried by said stem and engaging said seat, and means secured to said stem and rotatably adjustable with respect thereto in a plurality of predetermined positions to vary the operative position of said valve with respect to said seat, and automatic means cooperating with said first mentioned means for oscillating said valve 50 through a predetermined angle.
  3. The combination with a valve seat provided with a plurality of ports arranged about an axis, of a valve stem having its longitudinal axis coincident with said first mentioned axis, a valve carried by said stem and engaging said seat, being provided with a plurality of ports equal in number, arranged to communicate simultaneously and respectively with said ports in said seat, and means secured to said stem and rotatably adjustable with respect thereto in a plurality of predetermined positions to vary the operative position of said valve with respect to said seat and to bring any one of the ports of said valve into position to coöperate with a particular port of said seat, and automatic means coöperating with said first mentioned means for oscillating said valve through a predetermined angle.
  4. In a motor, the combination with a casing forming a part of the exterior of said motor, of a valve seat arranged within said casing, a valve engaging said seat, a valve stem arranged to oscillate said valve and projecting through said casing and outwardly from said motor, an arm secured to said stem outside of said casing and rotatably adjustable with respect thereto in a plurality of predetermined positions to vary the operative position of said valve with respect to said seat, and automatic means coöperating with said arm for oscillating said valve through a predetermined angle.
  5. A gas engine including means providing a combustion chamber and a distributing chamber, a valve seat separating said chambers and provided with a plurality of ports, an oscillatory valve provided with an equal number of ports arranged to communicate simultaneously and respectively with said first mentioned ports to provide an equal number of separate and direct passages of communication between said chambers, and means to vary the operative relation of said valve with respect to said seat.
  6. The combination with a valve case, of a valve seat arranged in said case and provided with a plurality of ports, a valve stem extending through said case and projecting outwardly therefrom, a valve secured to said stem and engaging said seat, said valve being provided with a plurality of ports arranged to coöperate respectively with said ports in said seat, and automatic means coöperating with said stem for oscillating said valve through a predetermined angle, said stem being adjustable with respect to said means in a plurality of predetermined positions to vary the operative position of said valve with respect to said seat.
  7. The combination with a valve seat having a plurality of angularly spaced ports radiating from a common axis, of a valve stem coaxial with said ports, a valve carried by said stem and engaging said seat, a crank

4
arm secured to said stem and rotatably adjustable with respect thereto in a plurality of predetermined positions to vary the operative position of said valve with respect to
5 said seat, and automatic means coöperating with said arm for oscillating said valve through a predetermined angle.

In witness whereof, I have hereunto set my hand this sixth day of June, 1911.

JOHN C. ENGLISH.
